UNITED STATES PATENT OFFICE.

EMORY J. GODMAN, OF JERSEY CITY, NEW JERSEY, ASSIGNOR TO STERLING SEAL COMPANY,
OF NEW YORK, N. Y., A CORPORATION OF MAINE.

BOTTLE-SEALING CAP.

No. 888,995.

Specification of Letters Patent.

Patented May 26, 1908.

Application filed September 13, 1907. Serial No. 392,702.

To all whom it may concern:

Be it known that I, EMORY J. GODMAN, of Jersey City, in the county of Hudson and State of New Jersey, have invented certain 5 Improvements in Bottle-Sealing Caps, of which the following is a specification.

This invention relates to certain improvements in a bottle sealing cap which embraces in its construction, a crown, a pendent skirt 10 and a joint forming gasket, as will herein-after fully appear.

It is a common practice in the manufacture of bottle sealing caps, to stiffen the edge of the skirt by beading or corrugation, and in 15 the sealing operation to contract in diameter the stiffened edge, in order that it may engage with the shoulder of the bottle head. In such practice, the stiffening of the edge of the skirt makes it necessary to employ con- 20 siderable power in the cap-affixing operation, due to the increase in area of cross section of the edge of the skirt; and in the reduction in diameter of the stiffened edge, its projection beyond the bottle neck is consequently re- 25 duced and does not therefore afford as pronounced a surface for engagement with the ordinary uncapping tool, as would be the case if the original diameter of the stiffened edge were maintained.

30 My invention as hereinafter more particularly described, consists in providing the edge of the skirt of the sealing cap with a flat horizontally-extending corrugated flange, and in the sealing operation, indenting the 35 skirt at a point above and independently of the flange so as to bring the inner surface of the skirt at that point slightly under and in contact with the shoulder of the bottle head. By this means, the stiffened flange is not dis- 40 turbed, but maintains its original diameter and furnishes a flat corrugated surface with which the uncapping tool will engage without slipping therefrom, in the act of opening the bottle.

In the further description of the said in- 45 vention which follows, reference is made to the accompanying drawing forming a part hereof, and in which,—

Figure 1 is a top view of the improved sealing cap, and Fig. 2 an exterior edge view of 50 the same. Fig. 3 is a sectional view showing the cap as secured to a bottle head.

Referring now to the drawing, 1 is the bottle head, and 2 the crown of the sealing cap. The skirt of the cap is denoted by 3, and the 55 corrugated flange of the cap by a.

4 represents the joint-forming gasket which is compressed between the lip b of the bottle head and the inner surface of the crown 2.

The indentation of the skirt above the 60 flange a is denoted by c and it is immaterial whether it is continuous, or consists of a multiplicity of depressions which are nearly in contact with each other.

In securing the cap to a bottle head the cap 65 is placed in position over the bottle, and while downward pressure is applied to the crown to compress the joint-forming gasket, the indentation c is effected by suitable mechanical appliances. 70

I claim as my invention:—

In combination with a bottle head having an annular shoulder, a sealing cap which consists in a crown, and a cylindrical skirt which is provided with a horizontally-extending exterior corrugated flange, the skirt of the cap independently of the flange, being reduced in diameter by indentation where the same is below and adapted to engage the shoulder of the bottle head, substantially as and for the 80 purpose specified. 75

EMORY J. GODMAN.
